UNITED STATES PATENT OFFICE.

WILLIAM A. LAWRENCE, OF CHARLOTTE, NORTH CAROLINA.

ATTACHMENT FOR ELECTRIC MOTORS.

1,001,152.

Specification of Letters Patent. Patented Aug. 22, 1911.

Application filed November 19, 1910. Serial No. 593,256.

To all whom it may concern:

Be it known that I, WILLIAM A. LAWRENCE, a citizen of the United States, residing at Charlotte, in the county of Mecklenburg and State of North Carolina, have invented a new and useful Attachment for Electric Motors, of which the following is a specification.

It is the object of this invention to provide a device adapted to be applied to an electric motor, or other machine, whereby, should the armature shaft of the motor run hot or become loose in its bearings, these facts will be communicated to an observer, through the automatic operation of a signal.

Another object of the invention is to provide an adjustable support in which a contact element is held, the contact element being releasable when an unusual degree of heat is generated in the machine, to close an electric circuit and to operate a signal; novel means being provided for actuating the contact element, subsequent to its release.

With the above and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed, without departing from the spirit of the invention.

In the drawings, Figure 1 shows in side elevation, and conventionally, an electric motor to which the device of my invention has been applied; Fig. 2 shows the invention in side elevation, the view being a detail enlarged from Fig. 1; Fig. 3 is a section upon the line A—B of Fig. 2, parts being shown in elevation; and Fig. 4 is a section upon the line C—D of Fig. 2, parts being shown in elevation.

In the drawings, the motor is denoted generally by the numeral 1, and the bearing by the numeral 2, the armature shaft 3 rotating in this bearing 2.

In carrying out the invention there is provided a ring 4, adapted to inclose the armature shaft 2, and to be secured to the motor 1. Ordinarily, this ring 4 is secured to the motor 1 by means of screws 5. An insulating sheet 6 is interposed between the ring 4 and the motor 1, and an insulating tube 7

surrounds each of the screws 5 so as to insulate the said screws from the ring 4. Moreover, insulating washers 8 are interposed between the heads of the screws and the outer face of the ring 4. The diameter of the opening in the ring 4 is somewhat greater than the diameter of the armature shaft 3, and by reason of this fact, a space 9 exists between the armature shaft 3 and the inner face of the ring 4.

In the edges of the ring 4 there are a plurality of threaded radial openings 10. In each opening 10 a screw 11 is mounted, the screw carrying a lock nut 12 which, engaging the ring 4, serves to hold the screw 11 against rotation. In the inner end of the screw 11 there is a channel 14, in which a contact element 15, ordinarily of copper or the like, is slidably mounted. This contact element 15 is held in place within the channel 14, and out of contact with the armature shaft 3 by means of one or more touches of solder 16, or other material which will melt at a very low temperature; in fact, melt at a temperature produced by the frictional heating of the armature shaft 3, the shaft 3 being typical of any moving part of a machine with which the device is adapted to be assembled.

A spring 17 is seated in each of the channels 14, this spring 17 acting compressively to force the contact element 15 outwardly, as soon as the solder 16 has been melted away.

A binding post 18 is secured to the ring 4, and another binding post 19 is secured to the motor 1. From the binding post 18 a conductor 20 leads to an electric bell 22, which may be taken to typify any sort of signal which may be operated electrically. Another conductor 21 leads from the binding post 19 to a battery 23, another conductor 24 leading from the battery 24 to the electric bell 22.

From the foregoing explanation of the circuit, it will be seen that the ring 4 upon the one hand, and the armature shaft 3 upon the other hand, form the terminals of an electrical signal circuit which is normally open.

In case the armature shaft 3 or its bearing should be unduly heated, the fusible material 16 will be melted, thus setting free one or more of the contact elements 15, whereupon the spring 14 will actuate the

contact elements 15 until one or more of them come into bearing with the armature shaft 3. The circuit will thus be closed, and the bell or other signal 22 be operated, thereby indicating at once, an undue heating in the motor.

It is to be noted, that should the armature shaft 3, although not overheated, work loose in its bearing, so as to have a gyrating motion, the shaft, under such circumstances, will come into contact with one or more of the elements 15, thereby closing the circuit and operating the bell 22.

It is to be seen that by rotating the screws 11 in the ring 4, the space between the contact elements 15 and the armature shaft 3 may be adjusted. When the screws 11 have thus been moved to the predetermined positions, they may be there held by rotating 20 the lock nuts 12 into abutment with the ring 4.

The ring 4 constitutes a holder for the screws 5, and the ring 4 and the screws 5 constitute the carrying member for the contact elements 15. The screws 11 act as supports for the springs 14 and the contact elements 15. Obviously, the fusible material 16 constitutes a thermostatic means whereby the contact elements 15 are held in place.

30 By reason of the fact that this fusible material 16 is united with the contact element 15 and with the screw 11, it will be noted that the screw 11 may be rotated to adjust the position of the contact element 15 with 35 respect to the armature shaft 3 without in any way breaking the continuity between the fusible material 16 and the contact element 15.

Having thus described the invention, what is claimed is:

1. In a device of the class described, a holder adapted to be secured to a machine in the vicinity of a moving part of the machine; a screw threaded into the holder and provided with a channel in one end; a contact element slidable in the channel to bear upon said machine part, thereby to close an electric signal circuit of which the said part and contact element are terminals; a spring in the channel, for sliding the contact element; and fusible material connecting the contact element with the screw to maintain the contact element spaced from said part. 40

2. In a device of the class described, a holder adapted to be secured to a machine in the vicinity of a moving part of the machine; a screw threaded into the holder and provided with a channel in one end; a lock nut upon the screw engaging the holder; a contact element slidable in the channel to bear upon said machine part, thereby to close an electric signal circuit of which said part and the contact element are terminals; a spring in the channel, for sliding the contact element; fusible material connecting the contact element with the screw to maintain the contact element spaced from said part. 55

In testimony that I claim the foregoing as my own, I have hereto affixed my signature in the presence of two witnesses. 70

WILLIAM A. LAWRENCE.
